UNITED STATES PATENT OFFICE.

JOSEPH W. MOSS, OF BEACON, NEW YORK.

UNIVERSAL QUICK-THAW TORCH.

1,341,514.

Specification of Letters Patent. Patented May 23, 1920.

Application filed December 13, 1919. Serial No. 344,716.

To all whom it may concern:

Be it known that I, JOSEPH W. Moss, a citizen of the United States, residing at Beacon, in the county of Dutchess and State 5 of New York, have invented certain new and useful Improvements in Universal Quick-Thaw Torches, of which the following is a specification.

This invention relates to improvements in 10 torch or burner attachments which are designed to spread the flame of a gasolene blow torch over an extended area and to confine the heat about a pipe for the purpose of thawing ice therein.

15 It is common practice for plumbers to use a blow torch to thaw frozen water pipes moving the flame from point to point over the frozen area. This is a slow and wasteful method owing to the fact that only a 20 small percentage of the heat of the flame is concentrated upon the pipe.

The object of my invention is to provide 25 an attachment for the ordinary plumber's torch which will not only spread the flame along the pipe but also causes it to follow around the contour of the pipe, heating it upon all sides. The spreader casing forms a reverberatory housing for the flame reflecting and directing it upon the pipe as 30 well as constituting a heating chamber inclosing a large portion of the pipe.

In the accompanying drawings, Figure 1 is a side elevation of a gasolene blow torch having attached to the burner a flame spreading device embodying my invention; 35 Figs. 2 and 3 are cross sectional views on the lines 2—2 and 3—3, respectively of Fig. 1; and Fig. 4 is a perspective view of one form of my attachment.

40 My flame directing and heat concentrating attachment is adapted to be secured to the burner tube 4 of an ordinary blow torch 5. The heating chamber and reverberatory housing comprises a tubular casing 8, having closed ends 9 provided with an 45 arcuate recess on one side conforming to the circular contour of the pipe, a longitudinal section of the casing being cut away to form an opening for the reception of the 50 pipe 10. Extending centrally from the casing opposite said opening is a tubular stem 12 adapted to slip over the end of the torch burner 4 and be secured by a set screw 14 or in any other suitable manner. The casing 55 wall about the opening both along the sides and at the ends is serrated, forming a

series of channels between the teeth 15 for the passage of the flames. This is an important feature of my invention as it provides a means for distributing the flames 60 uniformly along the pipe. The casing not only confines the flame issuing from the burner and forms a heating chamber but the arched inner wall reflects the heat and flames downwardly upon the pipe thus constituting a reverberatory housing and causes 65 the flames issuing through the passages between the teeth to follow around the contour of the pipe.

It is desirable that the housing should be 70 adjustable to adapt it to different sized pipes and for this purpose I provide an auxiliary side member 17 of arcuate shape to conform to the curvature of the inner wall of the housing. This auxiliary member may 75 be adjusted in or out of the casing to enlarge or diminish the size of the opening and may be secured in position, by means of set screws 18 which operate in slots in the 80 wall of the housing.

The advantages of my thawing attachment for blow torches will be especially appreciated by plumbers since it greatly enhances the efficiency of the flame not only because it spreads the flame over a greater 85 area but also because it confines the heat and concentrates it and by reason of the reverberatory effect produced by the inner arcuate walls, the flames are caused to follow 90 the contour of the pipe as they pass through the channels between the serrated edges of the side and end margins. While I have described in detail the particular construction illustrated in the accompanying drawings for the purpose of clearly disclosing an 95 embodiment of my invention, it will be understood that various modifications and changes can be made without departing from my invention.

I claim:—

1. A water-pipe thawing attachment for blow torches, comprising a tubular casing having closed ends and a longitudinal opening adapted to extend over a portion of the outer surface of a pipe, the marginal edges 105 adjacent said opening being provided with projections or serrations to engage the pipe and a tubular extension projecting from the casing opposite said opening and adapted to be secured to the burner tube of a blow 110 torch.

2. An attachment for blow torches as de-

100

105

110

fined in claim 1 and adjustable means for varying the size of the opening to adapt the casing to pipes of different diameters.

3. A water-pipe thawing attachment for
5 blow torches, comprising a tubular casing
having closed ends and a longitudinal opening
adapted to extend over a portion of the
outer surface of a pipe, the marginal edges
10 adjacent said opening being provided with
projections or serrations to engage the pipe,

an arcuate member conforming to the curvature
of the casing adjustably secured to move
outwardly or inwardly to vary the size of
said opening, and a tubular extension pro-
jecting from the casing opposite said open-
ing and adapted to be secured to the burner
tube of a blow torch. ¹⁵

In testimony whereof I affix my signature.

JOSEPH W. MOSS.
